PLIER TYPE STAPLING MACHINE

Fridolin Polzer, South Norwalk, Conn.

Application November 27, 1931, Serial No. 577,419

21 Claims. (Cl. 1—49)

This invention relates to new and useful improvements in stapling machines and has particular relation to a plier type stapling machine of the kind used for stapling together 5 the various pages of documents and the like.

An object of the invention is to provide a stapling machine of the character stated and which is of generally improved construction whereby staples may be accurately driven, the 10 machine is prevented from clogging, and the machine is easy to operate.

Another object is to provide a plier type stapling machine so constructed that the parts may be formed of sheet metal and may be easily and 15 quickly assembled whereby the machine may be manufactured at a relatively low cost.

Other objects and advantages will become apparent from a consideration of the following detailed description taken in connection with 20 the accompanying drawings wherein a satisfactory embodiment of the invention is shown. However, it will be understood that the invention is not limited to the details disclosed but includes all such variations and modifications 25 as fall within the spirit of the invention and the scope of the appended claims to which claims reference should be had for a definition of the invention.

In the drawings:

30 Fig. 1 is a side elevational view showing the improved stapling machine completely assembled, parts of the housing being broken away;

Fig. 1a is a side elevation of the front portion of the machine showing the position of the 35 pivoted housing during the operation of setting the staples;

Fig. 2 is a side elevational view of the same showing an assembly or disassembly operation;

Fig. 3 is a perspective view of the pivoted 40 or movable housing;

Fig. 4 is a perspective view of a part to be assembled on the pivoted or movable housing of Fig. 3;

Fig. 5 is a transverse sectional view taken 45 substantially along the line 5—5 of Fig. 3;

Fig. 6 is a perspective view of the follower mechanism parts being broken away;

Fig. 7 is a view partly in top plan and partly in section just under the top wall of the main 50 housing and on an enlarged scale;

Fig. 8 is a sectional view on an enlarged scale through the forward portion of the pivoted housing and showing the raceway and the plunger disposed therein in its retracted position;

Fig. 9 is a view similar to Fig. 8 but showing the relative location of parts as the plunger moves to drive a staple;

Fig. 10 is a perspective view on an enlarged scale of the plunger removed;

Fig. 11 is a perspective view on an enlarged scale of a removable closure for one end of the housing;

Fig. 12 is a view on an enlarged scale from the rear of the part Fig. 4;

Fig. 13 is an elevational view on an enlarged scale of the pivoted housing looking from the left in Fig. 3; and

Fig. 14 is a sectional view of the main housing alone substantially on line 14—14 of Fig. 2, the 70 dotted lines suggesting the manner of forming the said housing.

Referring in detail to the drawings the improved plier type stapling machine as here disclosed includes a main housing 15 here shown 75 as formed of a single piece of sheet metal. In the formation of the housing the sheet metal is folded to provide a bottom wall 16, side walls 17 and 18 and abutting portions 19 forming a top wall. The portions 19 are connected as by a 80 strap 20 to which the portions may be pinned or otherwise secured whereby the housing is held in shape. Also, formed integral with the housing is a rearwardly extending curved handle or grip 21.

The side walls 17 and 18 of the housing are cut away to provide the mouth or notch 22 into which papers or the like 22a to be stapled together are inserted. Disposed on the bottom wall 16 of the housing below the notch 22 is an 90 anvil bar 23 secured in place as by rivets 24 and being shaped to provide the anvil recesses 25 which bend or fold the prongs of the staples against the under side of the papers and thus clinch the staple in the usual manner after the 95 prongs have been forced through the papers by the plunger. At the front end the housing 15 may be closed as by a removable cap or closure member 26 while at its rear end the housing is left open for a purpose to be described. 100

Adjacent their forward edges and at the upper sides of the notch 22, the side walls 17 and 18 of the housing are notched as at 27 and the cap or closure 26 has upwardly curved portions 28 to engage in these notches when the closure is 105 assembled on the housing. The closure may be assembled on the housing by engaging the portions 28 in the notches 27 and then forcing the upper edge portion 29 of the closure over the reduced edge portions 30 of the side walls after 110

which a pin 31 may be inserted through the openings 32 in the closure which openings will be in registry with openings 33 in the side walls 17 and 18 of the housing. Other means may be employed for mounting this closure.

Disposed within the main housing 15 is a pivoted or movable staple supporting housing 34 also shown as formed of a single piece of sheet metal. Staple supporting housing 34 includes a longitudinally extending portion 35 which is hollow and within which is mounted a guide or guide bar 36 for a strip of staples 64 in the forward end portion of which is arranged a shear block 37, the block being secured in place as by a rivet 38. (See Figs. 8 and 9). As shown in Fig. 5 the guide 36 may be secured to the elongated portion 35 of the pivoted staple supporting housing as by rivets 39 and the upper edge portions of the portion 35 of the pivoted staple supporting housing are slightly inturned as at 40 whereby they are disposed in vertical spaced relation to the upper edges of the guide 36. The guide 36 is of substantially U-shape in cross section and may be formed from sheet metal.

Formed with the forward end portion of the portion 35 of the pivoted housing 34 is a part 41 adapted with the part 42 (see Fig. 4) to provide a head 43 containing a guideway and raceway in which a plunger will operate to drive staples. The part 41 of head 43 includes vertically extending side walls 44 having their upper ends turned toward one another as at 45 and the forward edges of these side walls are turned outwardly to provide surfaces 46 adapted to form one side of a guideway for the plunger as will later appear. Further, after the formation of the surfaces 46 the side walls are turned to have their edges face forwardly as at 47 to provide shallow walls defining the edges of the guideway.

The part 42 of the head 43 is also disclosed as formed of a single piece of sheet metal and this part includes side walls off-set as at 48 providing wall portions 49 and 50, the part being so proportioned that when assembled on the part 41 to form the head 43 the wall portions 49 are disposed against the forward end portions 51 of the elongated portion 35 of the pivoted staple supporting housing while the off-set 48 will be disposed on the forward portions of the inturned upper edges 40 of the portion 35 and the portions 50 will embrace the lower portions 52 of the side walls 44 of part 41. Part 42 also includes vertically extending portions 53 connected by outwardly off-set bight portions 54 and shaped to provide grooves 55.

In assembling the part 42 on the part 41 the portions 46 and 47 of the side walls of part 41 are received in the grooves 55 of the part 42, the parts being assembled by sliding part 42 downwardly over part 41. This will arrange the side portions of the part 42 as described above and the parts may be secured in assembled relation as by inserting a pin 56 through the openings 57 of the part 42 and 58 of the part 41 which openings will be in registering relationship. When the parts have been assembled as described a staple driver guideway 59 will have been provided including a staple raceway 59a (Fig. 8) at its lower end at the forward end of the staple guide 36, one side of the guideway being represented by the portion 46 of the part 41 and the opposite side being represented by the opposed surfaces of the grooves 55 of the

part 42, the edges of the guideway being defined by the shallow walls provided when the forward edges 47 of the side walls 44 of part 41 are turned to extend forwardly as above described.

As shown in Figs. 8 and 9 the guide 36 extends to one side of the raceway 59a, the shear block 37 being disposed in this end of the guide. Opposite the guide the part 42 of the head 43 carries a dog or pawl 60 pivoted as by a pin 61 and the forward portion of the bottom wall of the guide and the forward edge of the block are slotted or recessed as at 62 and 63 respectively to accommodate this pawl or dog in certain of its movements. The purpose of the pawl 60 is to prevent more than one staple entering the raceway at a time. That is, owing to the action of this pawl 60 a second staple may not enter the raceway until the first staple to enter the raceway has been driven therefrom. When a staple is in the raceway below the level of the top of the staple strip guide bar 36 the connecting bar of this staple indicated at 64a, Fig. 9 engages the front edge of the pawl or lever 60 and swings it to the position shown in Fig. 9 so that the upper lug portion 60a engages the forward staple of the strip still on the guide bar and prevents another staple entering the raceway until the first staple 64a has been forced from the raceway. The pawl is preferably so shaped as to push the staple strip back a short distance against the action of feed spring 71. This pawl or dog 60 constitutes a safety feature to prevent clogging of the machine by jamming of a plurality of staples in the raceway which might otherwise take place if the plunger were partly depressed and then allowed to its upper position without setting the staple. This safety device is fully disclosed and claimed in my prior Patent No. 1,829,537 issued October 27, 1931.

Guide bar 36 is adapted to receive a staple strip 64 and a spring pressed follower 65 is adapted to be mounted on the guide bar and normally act to urge the staple strip toward the raceway and feed the staples one at a time into the raceway. The follower is so shaped as to slide along the guide bar and is slidably mounted on a bar or rod 66 passing through a sleeve 67 at the underside of the follower, the ends of this sleeve passing through a slot in the top wall of the follower and folded against this wall as indicated at 65a, Fig. 6. On the rear end of the bar or rod 66 is a head 68 having a bayonet slot 69 to co-operate with a projection 70 (Figs. 1, 2 and 3) which may be pressed from the underside of the guide bar adjacent its rear end.

A staple strip may be disposed on the guide bar and then the follower is slipped over the guide bar and pushed forwardly to move the strip toward the raceway. The follower may have an upstanding lug 65b guided in the slot 35a and insuring proper engagement of the follower with the end of the staple strip. When the strip reaches the raceway further movement of the strip is impossible except as the staples are cut off by the plunger and further movement of the head 68 into a position over the end of the guide bar to dispose the lug 70 in the bayonet slot 69 and thus secure the parts together, is made possible by the telescoping of the rod or bar 66 through the sleeve 67. A spring 71 surrounding the rod 66 and bearing at one end against the sleeve 67 and at its other end against the head 68 yieldingly forces the follower 65 for-

wardly. This spring is compressed when the follower is assembled on the guide bar and the spring therefore constantly urges the staple strip toward the raceway.

5 With the cap or closure 26 removed the pivoted staple supporting housing 34 which includes the assembled head 43 is inserted into the main housing 15 through the forward end thereof. At its underside the elongated portion 35 of 10 housing 34 carries a clip 72 having downwardly extending perforated side portions 73 adapted to be brought into registry with openings 74 in the main housing whereby the housing 34 is pivotally mounted within the main housing as on a pivot 75. This clip may be secured to the underside of the portion 35 by any suitable means as a rivet 72a (Figs. 1 and 5).

In Fig. 10 is shown the plunger 76 when removed from the guideway 59 in the operating head 43. This plunger as shown is in the form of a strip of metal slotted as at 77 to straddle the dog or pawl 60 when the plunger is operated to drive a staple. Toward its upper end the plunger is provided with an opening 78 into 25 which projects a reduced extension 79 on an operating member or lever 80. Obviously the plunger 76 is to be reciprocated in the guideway 59 to set the staple.

Extending through the rear open end of the 30 main housing 15 is an operating handle 81 pivoted between the side walls 17 and 18 of the housing as on a pivot 82. The operating member or lever 80 likewise is pivoted on the side walls 17 and 18 of the housing as by means of a pivot 83. It will be noted especially by an inspection of Fig. 1 that the pivot 82 is intermediate the ends of the handle 81 and that the pivot 83 is intermediate the ends of the operating member or lever 80. From Fig. 7 it will 40 be clear that the inner end portion 84 of the handle 81 is bifurcated and has its extreme inner end portions turned toward one another to provide slightly spaced portions 85 between which extend one end portion of the operating member or lever 80.

The overlapping portions of the handle 81 and the member 80 are connected by a pin and slot connection comprising a pin 86 carried by the 50 extreme end portions 85 of the handle and a slot 87 in the member 80. It will be apparent that the member 80 being pivoted intermediate its ends the said member will serve to reverse the direction of movement of the inner end of the handle with respect to the motion delivered to the plunger. That is, as the outer portion of handle 81 is moved toward the corresponding portion of the handle 21 the inner end portion of handle 81 will move upwardly. This will 55 result in a corresponding movement of the rear portion of the member 80 with the result that the forward portion 79 of the member 80 will move downwardly operating the plunger to drive a staple.

A spring 88 is disposed about the pivot 82 and has one arm 89 bearing against the underside of the handle 81 to thus tend to raise it and has its other arm 90 engaging the elongated portion 35 of the pivoted staple supporting housing 34 forwardly of the pivot 75 for said housing. The 65 full function of this spring will later be described, but here it may be stated that the spring serves to return the parts to normal position after each operation of driving a staple. Operating member 80 adjacent its forward end 70 is rather sharply reduced to provide the exten-

sion 79. Immediately in the rear of this extension 79 the portion 91 of the member 80 is arranged to engage under the portions 45 of the part 41 of the operating head 43 as the parts return toward normal position whereby the pivoted housing 34 will also be returned to the normal position of Fig. 1 as will later appear.

As above suggested, each of the parts of the present stapling machine are preferably formed of sheet metal. The complete main housing 15 including the handle 21 is formed of a single sheet of metal and the pivoted staple supporting housing 34 including the part 41 of the operating head 43 is also formed of a single sheet of metal. The guide 36 may be formed of sheet metal and the part 42 of the operating head is formed of a single piece of sheet metal. From this it will be seen that substantially the entire machine may be formed of sheet metal stampings and that the cost of manufacture is therefore kept low.

After the guide has been secured in the pivoted housing 34 and the part 42 (Fig. 4) has been assembled on the part 41 of the pivoted housing the said pivoted housing is inserted through the forward end of the main housing as suggested in Fig. 2, it being understood that the cap or closure 26 has been removed or has not as yet been secured on the housing. The plunger 76 must, of course, be disposed in the guideway 59 prior to the insertion of the pivoted housing 34 into the main housing. As the housing 34 is being inserted into the housing 15 the handle 81 may be operated to throw the forward end of the operating member 80 downwardly into a position to enter the opening 78 in the plunger.

With the housing 34 disposed to have its pivot openings in its parts 73 aligned with the proper opening 74 in the main housing the handle 81 may be manipulated to operate the plunger for the purpose of determining whether or not the reduced portion 79 of the member 80 has entered the opening 78 in the plunger. Next, the pivot 75 is inserted through these registering openings whereby to pivotally mount the housing 34. In the foregoing description it has, of course, been assumed that the handle 81 and the operating member 80 were previously mounted in the housing, the assembling operation for these parts being apparent. The pivots 75, 82 and 83 may each be of the kind clearly shown in Fig. 7 and each include two parts inserted from the opposite sides of the housing 15 and threaded together. When the parts have thus been assembled the cap or closure 26 may be applied as already fully described.

Next a staple strip is disposed on the guide 36 and the follower mechanism assembled on the guide as already described. In the operation of the machine the papers to be stapled together are disposed in the mouth or notch 22 as indicated at 22a (Fig. 1a) and the handle 81 is then pressed in the direction of the handle 21. This results in a compressing of the spring 88 with the result that the pressure of the spring 135 is exerted through the arm 90 thereon on the pivoted housing 34 forwardly of its pivot 75 is materially increased. As this pressure is increased the pivoted staple supporting housing is rocked on its pivot so as to throw its forward 140 end, that is its end carrying the head 43, downwardly toward the anvil 25 until the forward portion of the pivoted housing engages the material to be stapled as shown in Fig. 1a, this movement being with the forward end of lever 145 150

30 as the walls 45 are pressed against the top edge of this lever by the force of spring arm 90.

Further downward movement of the handle 81 or further movement of this handle toward the handle 21 will result in the plunger being operated to drive a staple as the movable housing 34 is arrested, it being understood that there is some little play of the extension 79 in the opening 78 in the plunger. The initial movement of the handle 81 to operate or rock the pivoted staple supporting housing 34 as above described is also made possible through the pin and slot connection between the handle and the member 80. From what has been said it will be seen that before a staple is driven from the raceway and as a matter of fact before the plunger cuts a staple from the strip the pivoted staple supporting housing has been moved to dispose the lower open end of the raceway against the material to be stapled, and therefore the walls of the raceway will guide the staple as its prongs are forced through the articles to be stapled.

On the handle 81 being released after a staple has been driven the spring 88 acts first to start the handle back toward normal position. During this movement of the handle the operating member 80 will, of course, be rocked about its pivot and its portion 91 (Figs. 8 and 9) will engage the end portions 45 of the walls 44 of the member 41 with the result the pivoted staple supporting housing will have its forward end portion rocked upwardly to return it to its normal position. Of course, as the parts return toward normal position the plunger is drawn upwardly to its inactive position in the guideway above the point where the staples of the staple strip 64 are fed into the raceway.

This construction and arrangement provides plenty of leverage so that the staples can be driven with comparative ease and the device can be operated for a long time without tiring the operator.

Having thus set forth the nature of my invention, what I claim is:

45 1. In a plier type stapling machine, a housing having a handle rigid therewith, a handle pivoted to said housing, a staple supporting housing pivotally mounted in the first housing, a head on said pivoted housing, said head having a guideway providing a raceway therein, an anvil stationary on the first housing below said raceway, a plunger slideable in the guideway toward and from the anvil, a guide in the pivoted staple supporting housing for a staple strip, means for feeding the staple strip toward the raceway to dispense the first staple of the strip in the raceway below the plunger, and a connection between the pivoted handle and the plunger adapted on operation of said handle to permit swinging of the staple supporting housing toward the anvil and to move the plunger in a direction to drive a staple.

60 2. In a plier type stapling machine, a housing having a handle rigid therewith, a handle pivoted to said housing, a staple supporting housing pivotally mounted in the first housing, a head on said pivoted housing, said head having a raceway therein, an anvil on the first housing below said raceway, a plunger slideable in the raceway toward and from the anvil, a guide in the pivoted housing for a staple strip, a follower for normally urging the staple strip toward the raceway to dispose the first staple of the strip in the raceway below the plunger, a spring engaging the pivoted handle and the pivoted housing, a con-

nection between the pivoted handle and the plunger, said spring adapted on movement of the pivoted handle to rock the pivoted housing on its pivot to move its head toward the anvil, said handle on further movement adapted through its connection with the plunger to operate the same in a direction to drive a staple, and said spring adapted to return the parts to normal position on the pivoted handle being released.

85 3. In a plier type stapling machine, a housing having a handle rigid therewith, a handle pivoted to said housing, a housing pivotally mounted in the first housing, a head on said pivoted housing, said head having a raceway therein, an anvil on the first housing below said raceway, a plunger slideable in the raceway toward and from the anvil, a guide for a staple strip in the pivoted housing, a follower for normally urging the staple strip toward the raceway to dispose the first staple of the strip in the raceway below the plunger, a spring about the pivot of the pivoted handle and normally urging said handle toward inoperative position, said spring having an arm engaging the pivoted housing 100 forwardly of its pivot, a connection between the pivoted handle and the plunger, said spring adapted on the pivoted handle being moved against the action of the spring to rock the pivoted housing on its pivot to move its head in 105 the direction of the anvil, said handle on further movement adapted through its connection with the plunger to operate the same in a direction to drive a staple, and said spring adapted to return the parts to normal position on the handle being 110 released.

90 4. In a plier type stapling machine, a housing, a handle pivoted to said housing, a staple supporting housing movably mounted in the first housing, a head on said movable housing, said head having a raceway therein, an anvil on the first housing below said raceway, a plunger slideable in the raceway toward and from the anvil, a guide for a staple strip in the movable housing, means for advancing the staple strip toward the raceway to dispose the first staple of the strip in the raceway below the plunger, a connection between the handle and the movable housing, a connection between the handle and the plunger, and said handle adapted on initial movement to shift the movable housing to move its head toward the anvil and on further movement to operate the plunger in a direction to drive a staple.

95 5. In a plier type stapling machine, a housing, a handle pivoted to said housing, a staple supporting housing movably mounted in the first housing, a head on said movable housing, said head having a raceway therein, an anvil on the first housing below said raceway, a plunger slideable in the raceway toward and from the anvil, a guide for a staple strip in the movable housing, means for advancing the staple strip toward the raceway, a spring connection between the handle and the movable housing, a connection between the handle and plunger, said handle adapted on initial movement to compress the spring and shift the movable housing to move its head toward the anvil and on further movement to operate the plunger in a direction 140 to drive a staple, and said spring adapted to return the parts to normal position on the handle being released.

100 6. In a plier type stapling machine, a housing having substantially parallel side walls, a bot-

tom wall, an open end and a handle integral with its open end portion, said housing formed of a single sheet of metal, an anvil mounted in the housing, a head within the housing, said 5 head having a raceway therein movable toward and from the anvil, a guide for a staple strip, means for feeding the staple strip along the guide to feed the staples into the raceway, a plunger in the raceway and movable therein to 10 drive the staples, a pivotally mounted handle extending through the open end of the housing, and a connection between the pivoted handle and the plunger whereby on operation of the handle the head is shifted toward the anvil and 15 the plunger may be operated to drive a staple.

7. In a plier type stapling machine, a housing having substantially parallel side walls, a bottom wall, an open end and a handle integral with its open end portion, said housing formed of a single sheet of metal, a head within the housing, said head having a raceway therein, a guide for a staple strip, a follower for normally urging the staple strip along the guide to feed the staples to the raceway, a plunger in the raceway and 20 movable therein to drive the staples, a handle extending through the open end of the housing and pivotally mounted on a side wall thereof, an operating member arranged within the housing and pivoted intermediate its ends to a wall 25 of the housing, a connection between one end of the member and the pivoted handle, and a connection between the other end of said member and the plunger whereby on operation of the pivoted handle the plunger may be operated to 30 drive a staple.

8. In a plier type stapling machine, a housing having substantially parallel side walls, a bottom wall, an open end and a handle integral with its open end portion, said housing formed 40 of a single sheet of metal, a head within the housing, said head having a raceway therein, a guide for a staple strip, means for feeding the staple strip along the guide to feed the staples into the raceway, a plunger in the raceway and 45 movable therein to drive the staples, a handle extending through the open end of the housing and pivotally mounted on a side wall thereof, an operating member arranged within the housing and pivoted intermediate its ends, to a wall 50 of the housing, an operative connection between one end of said member and the pivoted handle, said plunger having an opening therein, and said operating member having an extension entering the opening in the plunger whereby on 55 operation of the pivoted handle the plunger may be operated to drive a staple.

9. In a plier type stapling machine, a housing, said housing having an open end, an anvil mounted in the housing, a head within the housing and movable toward and from the anvil, said head having a raceway therein, a guide for a staple strip, means for feeding the staple strip along the guide to feed the staples to the raceway, a plunger in the raceway and shiftable therein to 60 drive the staples, a handle extending through the open end of the housing and pivotally mounted on a wall of the housing, and a connection between the pivoted handle and the plunger whereby on operation of the handle the head 65 may be shifted toward the anvil and the plunger may be operated to drive a staple.

10. In a plier type stapling machine, a housing having an open end, a head within the housing, said head having a raceway therein, a guide for 70 a staple strip, means for advancing the staple

strip along the guide to feed the staples into the raceway, a plunger in the raceway and movable therein to drive the staples, a handle extending through the open end of the housing and pivotally mounted on a side wall thereof, an operating member arranged within the housing and pivoted intermediate its ends to a wall of the housing, an operative connection between one end of said member and the pivoted handle, and a connection between the other end of the member and the plunger whereby on operation of the pivoted handle the plunger may be operated to drive a staple.

11. In a plier type stapling machine, a housing having a handle rigid therewith, a handle pivotally mounted to said housing, a housing pivotally mounted in the first housing, a head on said pivoted housing, said head having a raceway therein, an anvil on the first housing below said raceway, a plunger slideable in the raceway toward and from the anvil, a guide in the pivoted housing for a staple strip, means for advancing the staple strip toward the raceway to feed the first staple of the strip into the raceway, an operating member arranged within the housing and pivoted intermediate its ends, an operative connection between one end portion of the member and the pivoted handle, and a connection between the other end portion of said member and the plunger whereby on operation of the pivoted handle the plunger may be moved to drive a staple.

12. In a plier type stapling machine, a housing having an open end, a handle extending through said open end of the housing and pivotally mounted on the housing, a housing pivotally mounted in the first housing, a head on said pivoted housing, said head having a raceway therein, an anvil on the first housing below said raceway, a plunger slideable in the raceway toward and from the anvil, a guide in the pivoted housing for a staple strip, means for advancing the staple strip toward the raceway to dispose the first staple of the strip in the raceway below the plunger, a spring engaging the pivoted handle and the pivoted housing, an operating member arranged within the housing and pivoted intermediate its ends, an operative connection between one end of said member and the pivoted handle, said plunger having an opening therein, said operating member having an extension entering the opening in the plunger whereby a connection is provided between the pivoted handle and the plunger, said spring adapted on the pivoted handle being moved against the action of the spring to rock the pivoted housing on its pivot to move its head in the direction of the anvil, said handle on further movement adapted through its connection with the plunger to operate the same in a direction to drive a staple, said spring adapted to return the handle and operating member to normal position on the handle being released, and said operating member having a part to engage a part of said head as the operating member moves toward normal position whereby the head and pivoted housing are also moved to normal position.

13. In a plier type stapling machine, a housing having opposite open ends, an anvil on said housing, a second housing, said second housing including a head having a raceway therein, a guide for a staple strip, means for feeding the staple strip toward the raceway, said second housing insertable and removable through one open end of the first housing, means for piv-

totally mounting the second housing in the first housing, a handle extending through the other open end of the first housing and pivotally mounted thereon, a spring engaging the pivoted handle and the pivoted housing, a connection between the pivoted handle and the plunger, said spring adapted on the pivoted handle being moved against the action of the spring to rock the pivoted housing on its pivot to move its head in the direction of the anvil, said handle on further movement adapted through its connection with the plunger to operate the same in a direction to drive a staple, and a removable cover closing the end of the first housing through which the second housing may be inserted and removed.

14. In a plier type stapling machine, a housing having opposite open ends, an anvil on said housing, a second housing, said second housing including a hollow elongated body portion having a head at one end thereof, said head including a pair of separable parts each made of a single piece of sheet metal and one of which is integral with said elongated body, said parts of the head co-operating to provide a raceway in the head, a guide in the elongated body portion of the second housing for a staple strip, means for feeding the staple strip toward the raceway, said second housing insertable through one open end of the first housing, means for pivotally mounting the second housing in the first housing, a handle extending through the other open end of the first housing and pivotally mounted therein, a spring engaging the pivoted handle and the pivoted housing, a connection between the pivoted handle and the plunger, said spring adapted on the pivoted handle being moved against the action of the spring to rock the pivoted housing on its pivot to move its head toward the anvil, and said handle on further movement adapted through its connection with the plunger to operate the same in a direction to drive a staple.

15. In a plier type stapling machine, a housing having a handle, a second handle pivoted to the housing, a second housing pivotally mounted in the first housing, a slideable plunger in the second housing, means in the second housing for guiding and feeding a staple strip to the plunger, an anvil on the first housing below the plunger, said second housing being movable about its pivot to shift the plunger and staple guide toward the anvil, an operative connection between the plunger and the pivoted handle, and means tending to move the pivoted housing toward the anvil.

16. In a plier type stapling machine, a housing having a handle, a second handle pivoted to the housing, a second housing pivotally mounted in the first housing, a slideable plunger in the free end of the second housing, means in the second housing for guiding and feeding a staple strip to the plunger, an anvil on the first housing beneath the plunger, the second housing being movable on its pivot to shift the plunger and staple guide toward the anvil, an operative connection between the second handle and the plunger for forcing it toward the anvil, and means for moving the free end of the pivoted housing toward the anvil prior to operation of the plunger on the initial movement of the handle.

17. In a plier type stapling machine, a housing having a handle, a second handle pivoted to the housing, a second housing pivoted in the first

housing, a guide for a staple strip in the pivoted housing, a removable head member mounted on the free end of the pivoted housing and providing a raceway for a plunger, a plunger in said raceway, means for advancing a staple strip along the guide to the raceway, a pivoted pawl mounted in the head member operated by a staple in the raceway to prevent a second staple entering the raceway until the first staple is discharged therefrom, an operative connection from the second lever to the plunger, an anvil in the first housing below the plunger, and means for an operation of the second handle shifting the free end of the pivoted housing toward the anvil prior to operation of the plunger.

18. In a plier type stapling machine, a housing having a handle, a second handle pivoted to the housing, a second housing pivoted to the first housing and having a raceway at its free end, a sliding plunger in the raceway, a guide for a staple strip in the pivoted housing, means for advancing the strip along said guide to feed the samples to the raceway, an anvil in the first housing under the plunger, a pivoted pawl operated by a staple in the raceway to a position to prevent entrance of a second staple to the raceway while the first staple is therein, an operative connection from the second lever to advance the plunger to set a staple, and means to advance the free end of the pivoted housing toward the anvil on initial movement of said second handle.

19. In a plier type stapling machine, a housing, a handle rigid with said housing, an anvil mounted in the housing, a head within the housing and movable toward and from the anvil, said head having a raceway therein, a guide for a staple strip, means normally urging the strip along the guideway to feed the staples to the raceway, a plunger movable in the raceway to drive the staples, a handle pivoted to the housing, an operating member pivotally mounted in the housing, an operative connection between said member and the pivoted handle, and an operative connection between said member and the plunger whereby on operation of the pivoted handle the head may move toward the anvil and the plunger operated to drive a staple.

20. In a plier type stapling machine, a one-piece housing folded up from sheet metal and including a handle projecting from one end, the side walls being provided with aligned notches leading from the other end of the housing to provide a mouth for insertion of papers to be stapled, an anvil at the lower side of the mouth, a staple supporting housing pivotally mounted in the first housing to swing toward and from the anvil, a staple driving plunger carried by said pivoted housing, and a second lever pivoted to the first housing and operatively connected to the plunger.

21. In a staple driving machine, a staple supporting housing comprising a piece of sheet metal folded into substantially U-shape and the side walls having upward extensions at their forward ends, a head member of folded sheet metal with the side walls folded to slidably engage the forward edges of said extensions to secure the head member on the first member to provide a guideway, a staple driving plunger in the guideway, means for feeding staples to the guideway under the plunger, and means for operating the plunger to set the staples.
